UNITED STATES PATENT OFFICE.

HENRY A. MCGRORY, OF DETROIT, MICHIGAN.

SAFETY DEVICE FOR ELEVATOR-DOORS.

No. 911,323.

Specification of Letters Patent.

Patented Feb. 2, 1909.

Application filed July 20, 1908. Serial No. 444,323.

To all whom it may concern:

Be it known that I, HENRY A. MCGRORY, citizen of the United States, residing at Detroit, county of Wayne, State of Michigan, have invented a certain new and useful Improvement in Safety Devices for Elevator-Doors, and declare the following to be a full, clear, and exact description of the same, such as will enable others skilled in the art to 10 which it pertains to make and use the same, reference being had to the accompanying drawings, which form a part of this specification.

My invention relates to an improvement 15 in safety devices for elevator doors and has for its object means whereby the elevator cannot be started when the elevator door is open. Provision is also made to prevent opening the doors of the elevator while the 20 car is moving from floor to floor.

A further object is to provide means whereby while one door is open no other door can be opened.

Another object is to provide means by 25 which any open elevator door may be closed from the basement or motor room and the car lowered without the necessity of the engineer or motorman ascending to the floor to close the door and to operate the controller 30 lever.

A still further object of this invention is to prevent creeping of the elevator due to leaking valves, or the arcing of the contact points, resulting from an improper setting 35 of the controller lever.

Other advantages and improvements will hereafter appear.

In the drawings: Figure 1 is a vertical central section through the elevator well and 40 car showing the door of the floor at which the car is stopped in the act of being opened. Fig. 2 is an end elevation of the operating sheave showing the reciprocating rack bar in locked relation therewith. Fig. 3 is a modification showing the reciprocating rack bar provided with a projecting knife blade adapted to enter between the springs of two fixed terminals conveniently located on the frame:—the parts thus serving as an electric 45 switch whereby the circuit may be opened or closed to control the operation of the elevator. Fig. 4 is a plan view of the modification shown in Fig. 3.

Referring now to the letters of reference 50 shown on the drawings:—A indicates the elevator well.

B, B', B², B³ indicate the several floors of the building.

C is the elevator car.

D, D', D² are sliding doors supported by suitable hangers in which are mounted pulleys adapted to traverse the track bars E, E', E².

F, F', F² indicate rack bars secured to the elevator doors.

G is a vertical shaft supported in suitable bearings and provided with pinions H, H', H², adapted to mesh with the rack bars F, F', F².

I is a bevel gear mounted on the vertical 70 shaft G and adapted to mesh with the gear J on the horizontal shaft J'. On the end of the shaft J' is a pinion J² meshing with the reciprocating rack bar K mounted on suitable friction rolls k.

L denotes the controller or starting lever mounted in the car and to which is connected the controller ropes M in turn passing around suitable pulleys M' and the sheave M²;—the sheave M² being mounted on a shaft adapted 80 to control the motive power whatever it may be.

N is a channel formed in the end of the sheave to receive the projecting end of the reciprocating rack bar K, as shown in Figs. 85 1 and 2.

O is a winding drum around which the cables for raising and lowering the car pass.

Having indicated the several parts by reference letters the operation of my improved safety device will now be explained.

The rack bars attached to the several doors are of such length that when the doors are closed they will be out of mesh with the several pinions H, H', H² attached to the 95 vertical shaft,—the object being to avoid opening any door other than the one at which the car stops. When the car is stopped at a floor, the operator upon opening the door causes the rack bar F to mesh with the pinion H of the vertical shaft thereby rotating the shaft and with it the bevel gear I and also the gear J of the shaft J',—on which is mounted the pinion J² controlling the movement of the reciprocating 100 rack bar K. Upon actuating the rack bar its projecting end is caused to enter the channel N of the controller sheave thereby locking the sheave against rotation. It will now be seen that any attempt to start the 105 elevator by operating the starting or controlling lever L in the car without first clos-

ing the door in order to withdraw the reciprocating rack bar from its locked relation with the sheave would be of no effect. So also it will be found impossible to open any 5 of the doors leading to the elevator well while one of them is open,—as the vertical shaft G on which are mounted the several pinions H, H', H² with which the rack bars on the doors mesh will be found locked 10 against rotation due to action of the open door.

To start the elevator, the door leading 15 into the car must be first closed. The act of closing the door serves to rotate the vertical shaft, due to the rack bar on the door meshing with the pinion on said shaft. This movement actuates the reciprocating rack bar K by means of the bevel gears I and J and the pinion J² thereby throwing the reciprocating rack bar out of locking engagement 20 with the controller sheave. The controller or starting lever L may now be operated, by which means the starting cable is actuated. This serves to partially rotate 25 the controller sheave,—shifting the position of the channel N so as to prevent the reciprocating rack bar from entering. It will thus be seen that when the elevator car is 30 passing from floor to floor none of the doors can be opened as the rack bars of the several doors cannot actuate their respective pinions on the vertical shaft;—being locked against rotation by the position of the reciprocating rack bar with reference to the operating 35 sheave.

One of the advantages of my improved safety device resides in the fact that the conductor or engineer may with perfect safety 40 enter the basement well of the elevator to oil or repair the parts and so long as the door through which he enters the well remains open he is assured that the elevator car cannot be raised or lowered by any one entering the car. Another advantage 45 resides in the fact that the conductor from the motor room can close any door and then lower the elevator car without the necessity of mounting to the floor on which the elevator car is left. This is accomplished by 50 first manually actuating the reciprocating rack bar K, the movement of which serves to rotate the vertical shaft and with it the pinion meshing with the rack of the open door,—then upon operating the controller 55 cable the elevator car may be lowered to the basement.

It will be noted that owing to the fact 60 that it is necessary to bring the controlling lever in the car to a certain fixed position each time in order that the doors may be opened, there is less liability of the elevator creeping due to leaking valves in hydraulic elevators, or the arcing of contact points of electric elevators. It being necessary to 65 bring the controlling lever to a certain fixed

position in order that the reciprocating rack bar may properly enter the channel formed on the end of the controller sheave, the proper position of the valves or other controlling devices is assured.

In the modification shown in Figs. 3 and 4, an electric circuit P is indicated leading to the controlling device (not shown),—the ends of the circuit being secured to fixed terminals having projecting spring contacts. 70 Mounted upon the reciprocating rack bar but insulated therefrom and adapted to travel with it is a projecting knife blade Q designed to enter the springs of the fixed terminals to close the circuit. Upon the car stopping at a floor, the door may then be opened, which action operates the reciprocating rack bar, thereby breaking the circuit, due to the opening of the switch by the withdrawal of the knife blade from between the springs of the fixed terminals. When the door is closed the electric circuit will be closed through the switch,—the car may then be started, as will be readily understood.

Having thus described my invention, what I claim is:—

1. In an elevator, a plurality of elevator doors, a vertical shaft adapted to be rotated and of a sufficient altitude to be directly engaged and rotated by suitable operating mechanism secured to each door, means for rotating said shaft secured to each of the doors but out of operating relation with the shaft when the doors are closed, whereby 100 when the shaft is rotated due to the action of one of the doors, the operating mechanism of the remaining doors will not be adapted to actuate said shaft until the open door is returned to its initial position.

2. In an elevator, a car, a controller for the motive power, means for actuating the controller mounted in the car, a plurality of elevator doors, a vertical rotatable shaft supported in suitable bearings and of sufficient altitude to be directly actuated by means secured to each of the doors, means connected with said doors for rotating said shaft, and means for governing the action of the controller due to the rotation of the shaft 110 whereby the car can only move as predetermined.

3. In an elevator, a car, a controller for the motive power, means for actuating the controller mounted in the car, a plurality of 120 elevator doors, a rack bar secured to each door, a rotatable shaft supported in suitable bearings, pinions thereon designed to mesh with the rack bars, and means for governing the action of the controller whereby 125 the car can only move as predetermined, consisting of a reciprocating bar adapted to be actuated by said rotatable shaft and to govern the action of said controller.

4. In an elevator, a car, a controller for 130

the motive power, means for actuating the controller mounted in the car, a plurality of elevator doors, a rack bar secured to each door, a rotatable shaft supported in suitable bearings, pinions thereon designed to mesh with the rack bars, and means for locking the controller whereby the car can only move as predetermined, consisting of a reciprocating bar adapted to be actuated by said rotatable shaft and to engage and lock said controller.

5. In an elevator, a car, a controller for the motive power, means for actuating the controller mounted in the car, a plurality of elevator doors, a rack bar secured to each door, a rotatable shaft supported in suitable bearings, pinions thereon designed to mesh with the rack bars, a shaft geared to said rotatable shaft, a pinion mounted thereon 15 designed to mesh with and actuate a reciprocating rack bar adapted to engage and lock the controller governing the operation

of the motive power, and said reciprocating rack bar, substantially as described.

6. In an elevator, a car, a controller sheave 25 for governing the motive power, a controlling lever mounted in the car, operating cables connecting the controller lever with the sheave, a plurality of elevator doors, a rack bar secured to each door, a rotatable shaft 30 suitably mounted, pinions thereon designed to mesh with the rack bars on the several doors, and a reciprocating bar actuated by means of the rotatable shaft and adapted to enter a channel or groove provided in the 35 wall of the sheave, whereby the latter may be locked against rotation.

In testimony whereof, I sign this specification in the presence of two witnesses.

HENRY A. McGRORY.
